UNITED STATES PATENT OFFICE.

CHARLES A. MEZGER, OF NEW YORK, N. Y.

SPARK-PLUG.

1,008,485.

Specification of Letters Patent. Patented Nov. 14, 1911.

Application filed November 28, 1908. Serial No. 484,159.

To all whom it may concern:

Be it known that I, CHARLES A. MEZGER, of the city of New York, borough of Brooklyn, State of New York, have invented certain new and useful Improvements in Spark-Plugs, of which the following is a full, clear, and exact specification, such as will enable others skilled in the art to which it appertains to make and use the same.

10 My invention relates to spark plugs for what is ordinarily termed the "jump spark" or high tension system of electrical ignition or gasoline and other internal combustion engines and the object of my invention is to construct such a plug so that it will in its contained parts, as contradistinguished from at some other point in the circuit, embody an auxiliary gap through which the current must pass and by which 20 the current is intensified.

A further object of the invention is to protect the central electrode in event of the breakage of the porcelain and consequent destruction of the insulation of said electrode.

Still a further object is to provide a packing which will insure an absolutely pressure tight joint between the porcelain and the metal shell without, however, subjecting 30 such porcelain to destructive strains and by means of which the unavoidable expansion and contraction of the porcelain may take place without cracking.

The invention involves various other features of importance and all will be fully set forth hereinafter and particularly pointed out in the claims.

Reference is had to the accompanying drawings, which represent, as an example, 40 the preferred embodiment of my invention, in which drawings,

Figure 1 is a longitudinal section of the plug; and Fig. 2 is an enlarged section of the metal band forming part of the packing.

45 The body of the plug is formed of the usual shell *a* receiving in its outer end the gland *b* and having its inner end threaded as at *a'* and provided with a terminal point *c*. The shell *a* receives the porcelain or equivalent insulation *d* and is formed interiorly with a shoulder *a''* between which and the inner end of the gland *b* the enlargement *d'* of the porcelain is received. The porcelain *d* is packed between 50 its enlargement *d'* and the shoulder *a''* on one hand and the inner end of the gland *b*

on the other. This is effected by two gaskets *e* of asbestos or other soft or fibrous material which are retained in place permanently by a band *f* of copper or other soft metal. This band is formed with an enlarged or thickened portion *f'* at its middle and with comparatively thin edge portions *f''*. The enlarged or thickened portion *f'* engages the middle portion of the enlargement *d'* of the porcelain seating against the same between the gaskets *e* and the thin edges *f''* embrace and cover said gaskets. After the gaskets and band are in place said thin edged portions *f''* are crimped or otherwise forced inward against and around the gaskets snugly to engage and hold the same. This packing, therefore, becomes a permanent part of the insulation *d* and may be freely removed from the plug with such insulation without danger of disarranging the packing. When the insulation *d* is in position in the plug and the gland *b* is screwed home a direct positive pressure is communicated from the gland *b* and shoulder *a''* 80 against the enlargement *d'* of the porcelain or other insulation *d* and a hermetic joint is effected and against the shoulder *a''* and gland *b* by the proper of other soft metal edge portions *f''* of the band *f*. This construction allows great pressure to be exerted by the gland without causing the gland or the shoulder of the shell *a* to impinge directly against the porcelain which impingement is a constant source of breakage of 90 porcelain in plugs of the sort to which my invention relates. At the same time the porcelain may be freely removed from the plug with the packing as an integral part thereof and the construction and manipulation of the plug thereby rendered far more simple than with the packing heretofore employed.

95 The central electrode *g* of the plug is received in the bore of the porcelain *d*, but instead of being in direct contact therewith, there is interposed between the porcelain and the electrode a sleeve *h* of an insulating material with no or a minimum coefficient of expansion. Such a material and that which I preferably employ is quartz which is fused and molded into the form of a cylinder tube and into which the central electrode is cemented or otherwise secured. The quartz tube containing the electrode is 100 then introduced and cemented into the porcelain as shown in the drawing. The result

of this construction is that owing to the absence of a co-efficient of expansion in the quartz and to its highly refractory nature it is not subject to the high temperature involved by the operation of the engine and, therefore, is not liable to breakage from contraction and expansion. The porcelain *d* furnishes a heavy mass of insulation which protects and reinforces the quartz or other tube *h* and said tube *h* is in itself a sufficient insulation for the electrode.

The insulation tube *d* terminates at and carries a cap *i* of brass or other metal which is fastened down over an enlargement on the upper end of the porcelain and which is adapted to be connected with the feed wire in any desired manner, preferably by what is known as a spark plug clip. The upper or outer end of the central electrode *g* terminates just short of the inner surface of this cap *i* and in this manner a gap *k* is formed. Said gap is, therefore, within the plug as an embodied part thereof and in this manner I increase in the intensity of the spark passed at the inner end of the plug without the disadvantage and difficulty of a gap constructed in the wired portion of the circuit. The cap *i* has no opening through its center and serves the purpose not only of permitting connection of the positive wire with the plug, but also as a cover and protector for the upper end of the parts *d*, *h* and *g*.

Having thus described my invention, what I claim as new and desire to secure by Letters Patent of the United States is:

1. A spark plug having an insulation mass with an enlargement, packing gaskets surrounding the plug at said enlargement and a soft metal band surrounding the enlargement and inclosing said gaskets to hold them upon the insulation mass.

2. A spark plug having an insulation mass with an enlargement, packing gaskets surrounding the plug at said enlargement and a soft metal band surrounding the enlargement and inclosing said gaskets, the edges of the band being rolled around said gaskets to hold them permanently and securely in place on the insulation mass.

3. A spark plug having an insulation mass with an enlargement, packing gaskets surrounding the plug at said enlargement and a soft metal band surrounding the enlargement and inclosing said gaskets, said band having an enlarged middle portion lying between the gaskets to stiffen the band and space the gaskets.

4. A spark plug having an insulation mass with an enlargement, packing gaskets surrounding the plug at said enlargement, and a soft metal band surrounding the en-

largement and inclosing said gaskets, said band having an enlarged middle portion lying between the gaskets to stiffen the band and space the gaskets and the thin edged portions of the band being rolled around the gaskets.

5. A spark plug having an insulation mass with an enlargement, a packing gasket encircling the mass at such enlargement and directly contacting therewith and a metal band surrounding the enlargement and encircling said gasket.

6. A spark plug having an insulation mass with an enlargement, a shell in which the insulation mass is disposed and limiting the longitudinal movement of said mass in one direction, a packing gasket surrounding the mass at one end and a metal band surrounding the enlargement and encircling said gasket and having one end contracted to prevent longitudinal movement of said end past the enlargement.

7. A spark plug having a main insulation tube, a refractory insulation tube contained within the main insulation and formed of a material having a minimum co-efficient of expansion, a central electrode contained within said refractory insulation tube and terminating short of said second insulation tube and a metal cap mounted on the outer end of the main insulation and extending over the outer end of the central electrode out of actual electrical contact therewith.

8. A spark plug having a shell presenting a shoulder intermediate its ends, an insulation mass disposed therein and presenting an annular enlargement adjacent to said shoulder, separate gaskets encircling said mass above and below the center of said enlargement and a sheet metal casing encircling said gaskets and said enlargement and having its upper portion contracted above the upper gasket and having its opposite end contracted below the lower gasket.

9. A spark plug having a shell presenting an annular shoulder, an insulation mass disposed therein and presenting an annular enlargement adjacent to said shoulder, separate gaskets encircling said mass above and below the center of said enlargement, and a soft metal casing encircling said gaskets and said enlargement and contracted above the upper gasket and contracted below the lower gasket.

In testimony whereof I have signed my name to this specification in the presence of two subscribing witnesses.

CHARLES A. MEZGER.
